PRESSURE UNIT FOR INTAGLIO PRINTING

Application filed October 9, 1929. Serial No. 398,289.

This invention relates to the art of intaglio printing and its object is to improve the pressure-applying unit in devices used for this purpose.

6. By reason of the way in which intaglio plates are made the surface of such a plate is not a true plane, even in those parts where no engraved lines occur. Some of the engraved parts as a whole are in a slightly different plane from other parts considered as a whole and, in addition, there are slight irregularities of surface which are the result of the hardening process to which these plates are subjected. These general irregularities 10 of surface are referred to in the following description and claims as "major irregularities". In addition to these are the depressions of the engraved lines into which the paper to be printed must be forced by the pressure-applying means of the press. In preparing a plate for printing, according to well known practice, various methods of "make ready" have been employed to take care of what might be the major irregularities. 15

The present invention is also an improvement on the device disclosed in our application Serial No. 385,504, filed August 13, 1929, and in said application we disclose an arrangement of printing unit whereby the "make ready" methods heretofore employed are entirely eliminated and the major irregularities fully compensated for.

20 In said application there is disclosed an intaglio printing press in which one or more fluid pressure containers are arranged in a printing head. Each of these fluid pressure containers is provided with a flexible wall adjacent the printing surface of the plate. In the particular disclosure of the application the flexible wall consists of a bag of rubber or other suitable flexible material into which fluid pressure is supplied after a piston, upon 25 which the plate to be printed is supported, is brought up into contact with the metal portion of the pressure container.

An object of the present invention is the provision of means for producing very sharp lines over the entire printed surface.

A further object, therefore, of the present invention is to provide a pressure unit for printing from an intaglio plate, or from a plurality of such plates, wherein the same movement of the piston or bed, of the press, 55 which brings the plate and pressure unit together also causes printing. This we accomplish by introducing between the substantially inflexible base of the pressure head, and the plate, a medium which is flexible and which is so confined that it will distribute the pressure to different portions of the surface of the plate, irrespective of its major irregularities. 60

Theoretically, and, as we have found, practically, it takes less pressure to distort the paper into the wide lines of the engraved portions of the plate than into the narrow lines. The added pressure necessary to produce perfect impressions of the narrow lines creates 70 what for convenience we term an "ink pressure" in the wide lines. This pressure squeezes the ink out of the lines against the locking pressure of the paper at the edges of these lines, thus causing a feathering or blurring of the wide lines which destroys their sharpness. 75

This fault is present in the ordinary methods of intaglio printing and heretofore it has been difficult, if not impossible, to eliminate 80 it entirely.

In the ordinary process of printing, a steel roller, known in the art as the D roller, furnishes the pressure for the printing. In order, however, that the paper may be squeezed into the various lines forming the engraved portion of the plate, it has been found necessary to use a matrix material adapted to the rigid printing roller and this material must be sufficiently pliable or flexible to be forced 85 into the engraved lines, by the resistance of the roller,—at all points of the plate and it is this necessary quality of the matrix material that causes the feathering or blurring 90 above referred to. 95

We have found that to some extent the same feathering exists in the pressure unit forming the subject matter of our application above referred to, because we use a pressure container of rubber or similar substance 100

which likewise, in conforming to the engraved lines, produces feathering where such lines are wide.

In the present invention this feathering is entirely overcome and sharp lines produced by the provision of a material interposed between the pressure head and the matrix material commonly used, the interposed material having such flexibility that it will readily conform to the major irregularities of the plate and therefore transmit the pressure applied thereto. Said material, however, is not sufficiently flexible to readily conform to the engraved portions of the plate. The matrix material is relied upon to enter these engraved portions. Furthermore, we back up this flexible material with a flexible medium interposed between the substantially inflexible surface of the pressure unit, and the material, such medium having such flexibility that it will distribute the pressure over the surface of the plate.

This medium may be a fluid such as water, introduced into a pressure container or permanently confined, to produce the printing impression after the plate and printing head are brought together; or such medium may be a solid of the proper degree of flexibility and also confined so that the movement to contact the plate with the medium and the printing impression takes place as a part of the movement.

While the invention is particularly applicable to the type of pressure head disclosed in said application we do not intend that our claims shall be limited to its use with any particular kind of pressure head or pressure unit.

Various other important features of the invention will become apparent from the following more detailed description with reference to the accompanying drawings, in which

Figure 1 is an elevation more or less diagrammatic, showing a pressure head capable of printing from several plates at one operation;

Figure 2 is a fragmentary sectional view of a plate holder, plate and pressure container, and illustrating the blurring or feathering effect referred to;

Figure 3 is a similar sectional view showing how the feathering is overcome by the present invention;

Figure 4 is a perspective view of the parts shown in Figure 3, but on a smaller scale and more complete;

Figure 5 shows a confined, flexible medium, which may be used instead of the pressure container of Figures 2 or 3; and

Figure 6 is another form which said confined, flexible medium may take.

Referring to the drawings, and more particularly to Figure 1, there is shown a piston 5 which is similar to the piston having a like reference character in our application

Serial No. 385,504, above referred to. Between the piston 5 and the head 4 are one or more plate holders each carrying an engraved plate. Four of such plate holders with their plates are shown in Figure 1. The lowest plate holder 12 is in immediate contact with the piston. The plate is indicated at 13 and immediately above this is shown a pressure container 6. In order to appreciate the advantages of the present invention it will be necessary to describe in a general way the mode of operation of the printing head disclosed in our prior application above referred to. In said device, printing pressure is applied to the plates through the medium of fluid pressure containers. Each of these containers consists of a metal plate recessed on its lower face and cemented on the recess is a bag of rubber or other flexible material having the corners reinforced by leather. The flexible container or bag is shown at 16, Figure 2, and fluid, such, for instance, as water, may be introduced into the container through a connection 18 tapped into one side of the container as shown at 19, Figure 1. The pressure head or cap of the press is properly connected with a base to sustain the necessary pressure.

The construction is such as to produce a greater pressure tending to hold the various plate holders and containers against the head 4 than is applied within the containers themselves.

Also as described in said application, the movement of the piston 5 to close the head does not of itself directly apply the printing pressure. This is subsequently applied by introducing fluid pressure into the containers. In the present invention we provide a type of flexible medium through which the printing is done by the direct pressure of the piston.

Reverting now to the first object of the invention and referring to Figure 2, the engraved depressions in the plate 13 are shown at 50, 51 and 52. These are shown somewhat exaggerated as to size in order to illustrate the feathering action to which reference has already been made in the opening paragraphs of this specification. Each of these depressions is filled with ink prior to the positioning of the plate within the printing head, and due to the ready flexibility of the wall of the container 6 there is a greater distortion of its lower portions into the wider engraved portions than in the narrower ones. In the depression 50, for instance, the container is distorted a considerable distance. It is distorted less in the depression 52 and very little in the depression 51. When the flexible container is distorted into the wider depressions there is a slight squeezing out of the ink around the edges and this causes a blurring or feathering of the lines and the finished print is not entirely sharp.

We have found that this difficulty, however, can be completely overcome by the present invention.

One means for accomplishing this is illustrated in Figure 3 which is an enlarged section of a portion of a plate holder, plate, and pressure head. As here illustrated, it is not necessary to use the flexible bag 16, although this may be used. It is sufficient to have the base plate 6 recessed and fluid is supplied to the recess through the conduit 18 as in the device shown in Figure 2, which is similar to that described in our application.

The lower face of the recess is covered by a wall 53 of material which may be of metal or other suitable substance.

In the form of device shown in Figure 3 water or other substantially incompressible fluid is the medium through which pressure applied to the base 6 is transmitted to the wall, and since the fluid is substantially incompressible and flexible it distributes the pressure applied to it.

The wall substance, therefore, must be sufficiently flexible to accurately transmit this pressure and conform to the major irregularities of the surface of the printing plate. It must not, however, be so flexible as to readily conform to the engraved portions of the plate.

Any substance having the degree of flexibility within these limits may be used.

In order that the paper may be forced into the engraved portions of the plate, a matrix material 54, such as is commonly used for this purpose, is interposed between the wall substance and the plate.

By the construction above described, printing pressure is distributed over the surface of the plate and the relatively higher portions thereof are not subjected to materially greater pressure than the lower portions. With such a construction, therefore, the impression is very sharp and the feathering or blurring of the wider lines does not occur.

In Figure 5 we have shown a confined flexible medium and in Figure 6 another form which this medium may take.

In Figure 5 the base 6 is recessed as in the previously described form, and the flexible medium, which in this form is illustrated as a fluid 60, is confined within a fluid container 61. This container may consist of a rubber bag having its edge 62 reinforced with leather or other suitable material. It is also confined around its lower edge by a frame 63 of metal and preferably a face plate 64 is provided to prevent the bag from sagging. The lower portion of the fluid container extends somewhat below the surface of the base plate 6 and sufficient fluid is originally introduced into the bag to completely fill it, and the bag is then permanently sealed. As the piston rises and the surface of the plate, with an interposed layer of matrix material, contacts

compression of the fluid container due to slight elasticity of its walls and to the elasticity of the leather or other reinforcement. This compression, however, is very slight and the parts are so proportioned that when the piston has taken up this compression, the gap between the piston and the wall 64 is very small. Since the confined fluid is substantially incompressible the slightest further movement of the piston will apply printing pressure.

This form of device may be preferable to that shown in Figure 3, because it insures somewhat faster operation of the press.

It will be remembered that the Figure 3 construction follows the method described in our application above referred to, in which the piston and all of the containers 6 are moved into contact prior to the introduction of the fluid within the containers. This is necessary to prevent a blow-out and the timing must be such as to insure the pressure being introduced within the containers subsequent to the closing of the parts. With the construction of Figure 5, therefore, a simpler mechanism may be used.

Figure 6 shows another form which the confined flexible medium may take. This figure is quite similar to Figure 4 and there is placed within the recess of the plate 6 a flexible medium 70 which is a solid having the desired flexibility, and a substance suitable for this purpose is substantially pure rubber. Rubber of this character is substantially incompressible and it may be made sufficiently flexible to equalize the pressure in different parts of the plate due to surface irregularities. The flexibility, however, need not be greater than is necessary to do this and therefore in using such a medium it would be necessary to interpose a matrix material of sufficient flexibility to conform to the engraved portions of the plate.

The solid material, whether rubber or other substances having the required properties, may, however, have a flexibility sufficient to conform to the engraved portions of the plate and in this event, to get a sharp impression in printing, it would be necessary to interpose between the medium and the printing plate, a sheet of material having the properties already described as possessed by the wall 53. This may be loosely placed in position since it does not act as a retaining wall.

In the form shown in Figure 6 the flexible medium is confined by a metal frame 71 extending entirely around the lower edge of the solid flexible medium, which frame extends somewhat into the recess in the base plate 6, as shown. In this figure a sheet of matrix material 54 similar to that described in connection with Figure 3 is interposed between the medium 70 and the paper which is indicated at 55, the plate being indicated at 13. In

this form of device, also, the same movement of the piston which brings the various elements together likewise produces the printing impression since the lower edge of the 5 medium 70 extends slightly below the surface of the plate 6.

It is to be noted that the wall 53 of suitable substance, may be used with the flexible containers described in our co-pending application 10 above referred to, and is not limited to the form of the invention shown in Figure 3. As illustrated in Figure 2 and in Figure 3 the flexible medium is confined only during the actual printing and is not permanently 15 confined as in the forms of the invention illustrated in Figures 5 and 6.

It is also to be noted that the material 53 need not necessarily be a separate and distinct unit from the bag or container 61 as illustrated 20 in Figure 5, or the solid medium 70 as shown in Figure 6. Such wall may be a surface integral with the container 61 or the medium 70, but sufficiently inflexible so that it will not readily conform to the engraved 25 portions of the plate.

Other variations not specifically enumerated may be resorted to within the scope of the invention and without departing from the spirit thereof.

30 What is claimed as new is:

1. A pressure unit for printing from an intaglio plate, said unit including a substantially inflexible base, a confined flexible medium adjacent the pressure face of the base, 35 and a material overlying said flexible medium and through which the printing pressure is applied to the plate, said medium having such flexibility that it will distribute the pressure over the surface of the plate and 40 said material having such flexibility that it will transmit the pressure to the plate as determined by the distortion of the medium and conform to the surface variations of the plate, but not sufficiently flexible to readily 45 conform to the engraved portions thereof.

2. A pressure unit for printing from an intaglio plate, said unit including a substantially inflexible base recessed for a portion of its area, a wall overlying said recessed area 50 of material sufficiently flexible to readily conform to the major irregularities of the plate but not sufficiently flexible to readily conform to the engraved portions thereof, and a constant volume flexible medium within 55 the recess.

3. A pressure unit for printing from an intaglio plate, said unit including a substantially inflexible recessed base, a wall overlying 60 said recess and a constant volume flexible medium within the recess, and through which medium and wall printing pressure is applied to the plate.

4. A pressure unit for printing from an intaglio plate, said unit including a substantially inflexible recessed base, a wall over-

lying said recess, a constant volume flexible medium within the recess, and a matrix material adjacent the wall adapted to contact with the material to be printed.

5. A pressure unit for printing from an 70 intaglio plate, said unit including a substantially inflexible base, a flexible medium adjacent the pressure face of the base, and a material overlying said flexible medium and through which the printing pressure is applied to the plate, said medium having such flexibility that it will distribute the pressure over the surface of the plate and said material having such flexibility that it will transmit the pressure to the plate as determined by 80 the distortion of the medium and conform to the surface variations of the plate, but not sufficiently flexible to readily conform to the engraved portions thereof.

6. A pressure unit for printing from an 85 intaglio plate, said unit including a substantially inflexible base, a confined flexible medium adjacent the pressure face of the base and a material separate from the confining means overlying said flexible medium and 90 through which the printing pressure is applied to the plate, said medium having such flexibility that it will distribute the pressure over the surface of the plate and said overlying material having such flexibility that 95 it will transmit the pressure to the plate as determined by the distortion of the medium and conform to the surface variations of the plate but not sufficiently flexible to conform to the engraved portions thereof.

7. A pressure unit for printing from an intaglio plate, said unit including a substantially inflexible base, a confined flexible medium adjacent the pressure face of the base and a material adapted to be inserted 100 between the flexible medium and the plate, said medium having such flexibility that it will distribute the pressure over the surface of the plate and said material having such flexibility that it will transmit the pressure 105 to the plate as determined by the distortion of the medium and conform to the surface variations of the plate but not sufficiently flexible to conform to the engraved portions thereof.

Signed at New York, N. Y., this fifth day of October, 1929.
